(57) **CLAIM**

The ornamental design for a cantilevered workspace mount for flat panel displays, as shown.

DESCRIPTION

FIG. 1 is a top, left isometric view of an embodiment of a cantilevered workspace mount for flat panel displays showing our design in a vertical configuration.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof; and,

FIG. 7 is bottom plan view thereof.
